UNITED STATES PATENT OFFICE.

SAMUEL MELLINGER, OF MOUNT PLEASANT, PENNSYLVANIA.

HORSE HAY-RAKE.

SPECIFICATION forming part of Letters Patent No. 322,948, dated July 28, 1885.

Application filed December 20, 1883. (No model.)

To all whom it may concern:

Be it known that I, SAMUEL MELLINGER, of Mount Pleasant, in the county of Westmoreland and State of Pennsylvania, have invented certain new and useful Improvements 5 in Horse Hay-Rakes; and I do hereby declare that the following is a full, clear, and exact description of the invention, which will enable others skilled in the art to which it appertains to make and use the same, reference being had 10 to the accompanying drawings, which form a part of this specification, and in which—

Figure 1 is a perspective view of a portion of my improved rake-head and axle. Fig. 2 15 is a cross-section of the same.

Similar letters of reference indicate corresponding parts in both the figures.

My invention has relation to horse hay-rakes; and it consists in the improved construction and combination of parts of the 20 rake-head, as hereinafter more fully described and claimed.

In the accompanying drawings, the letter A indicates the head, which is made of sheet 25 metal of a suitable thickness, and formed open at the under side, being U-shaped in cross-section. The edges or flanges B of the head are bent together at the ends of the head, forming round tapering ends C, upon

which sleeves D are slipped, which sleeves 30 serve as spindles for the wheels which turn upon them, while the sleeves at the same time serve to hold the flanges together. The teeth G are preferably of the construction shown in the drawings, formed with bails H, and having 35 their upper ends, I, passed through perforations F in the flanges of the head; and links K are hooked over the bails H, which rest on top of the rake-head, and over the ends I, and are held in place by keys J, fitting in the 40 bails H.

Having thus described my invention, I claim—

A rake-head for a horse hay-rake, formed of sheet metal bent into an inverted U-shaped 45 form in cross-section, having the lower flanges bent in toward each other at the ends, forming tapering spindles or axles for the supporting-wheels, and provided with tapering sleeves 50 fitting upon them, as and for the purpose shown and set forth.

In testimony that I claim the foregoing as my own I have hereunto affixed my signature in presence of two witnesses.

SAMUEL MELLINGER.
